CLAIM

[21] Appl. No.: 811,549

The ornamental design for an automobile rear bumper, as shown and described.

DESCRIPTION

[22] Filed: Dec. 20, 1985

FIG. 1 is a perspective view of an automobile rear bumper showing our new design, it being understood that the broken lines are for illustrative purposes only;

[52] U.S. Cl. D12/169

FIG. 2 is an enlarged top plan view thereof;

[58] Field of Search D12/169, 181; 293/102, 293/113, 117, 120, 121

FIG. 3 is an enlarged side elevation view thereof;

FIG. 4 is an enlarged cross-sectional view taken along line 4—4 of FIG. 2; and

FIG. 5 is an enlarged cross-sectional view taken along line 5—5 of FIG. 2.
